Primary Examiner — Sheryl Lane(74) *Attorney, Agent, or Firm* — Banner & Witcoff, Ltd.(57) **CLAIM**

The ornamental design for a display screen with graphical user interface, as shown and described.

DESCRIPTION

FIG. 1 is a front view of a display screen with graphical user interface showing our new design;

FIG. 2 is a front view of the display screen with graphical user interface of FIG. 1 shown on a device;

FIG. 3 is a front view of the display screen with graphical user interface showing an alternative embodiment of our new design;

FIG. 4 is a front view of the display screen with graphical user interface of FIG. 3 shown on a device;

FIG. 5 is an enlarged view of the claimed portion of FIG. 1; and,

FIG. 6 is an enlarged view of the claimed portion of FIG. 3. The broken-line showing of the text in FIGS. 1-4 and the remainder of the device in FIGS. 2 and 4 is for environmental purposes only and forms no part of the claimed design. The broken-line showing of the encircled icon, the remainder of the user interface, and the remainder of the display screen is for environmental purposes only and forms no part of the claimed design.

1 Claim, 6 Drawing Sheets(56)
